FASTENING MEANS FOR BOTTLE CUFFS
OR THE LIKEClaude D. Painter, San Francisco, Calif., assignor
to Harry F. Borden, San Francisco, Calif.

Application August 10, 1938, Serial No. 224,150

1 Claim. (Cl. 24—17)

This invention relates to bottle cuffs or devices formed of paper or similar material which are placed upon bottles or similarly shaped containers, and pertains particularly to fastening means employed to secure together the ends of a paper blank to form and retain it in a cuff-like shape.

The value of the advertising space afforded by a paper cuff placed around a bottle may readily be appreciated, and several forms of devices are already known for this purpose. The qualities most to be desired in such a device are attractive appearance, ease in assembling and applying the device to the bottle, and durability of construction which will result in the cuff's retaining a neat appearance and remaining in its intended place on the bottle notwithstanding the careless handling to which it may be subjected.

It is the object of the present invention, therefore, to provide fastening means for a bottle cuff that will make possible the assembly of the cuff with great facility and that will hold the cuff rigidly in its assembled position both before it has been applied to the bottle and after its application thereto.

One form of the invention is illustrated in the accompanying drawing and described in detail in the following specification wherein reference is made to the drawing and wherein other objects and advantages of the invention are made apparent.

In the drawing—

Fig. 1 is a fragmentary view of a bottle with a bottle cuff made in accordance with the present invention in place thereon;

Fig. 2 is a fragmentary perspective view showing the two ends of the bottle cuff just prior to their being fastened together, and illustrating details of the fastening means;

Fig. 3 is a plan view of a blank from which the cuff is assembled by bending and fastening together its overlapping ends; and

Fig. 4 is an elevation of the fastening means in assembled position as viewed from the interior of the cuff.

Referring more particularly to the drawing, Fig. 1 shows a bottle cuff having the fastening means of the present invention applied to a bottle having the general contour of a milk bottle. It is to be understood, however, that the shape of the cuff will be varied to fit any desired shape or style of container. The blank from which the cuff is assembled is shown in Fig. 3 as comprising three connected disk-like members 10 and flaps 11 and 12 formed at its opposite ends and embodying the fastening means which serve when

the blank is assembled to its cuff-like shape with the flaps 11 and 12 overlapping each other to retain it in this shape both before and after it has been applied to the neck of a container. The shape of the members 10 is a result of artistic design and has no bearing on the function of the fastening means presently to be described, as the general outline of the cuff may be varied widely to produce different artistic effects.

The flap 11, at the left-hand end of Fig. 3, 10 is provided with a semi-circular tab 13 projecting from the end thereof, and a semi-circular slit 14 cut in a position to form an identical tab 15 which may be bent out of the plane of the flat blank. The tab 13 is bendable along the dotted line 16, 15 and the tab 15 is similarly bendable along the dotted line 17, which lines are of the same length and parallel to each other. It will be apparent as the description proceeds that the tab 13 need not project beyond the end of the flap 11, but 20 might, by a mere change in design, be in the same form as the tab 15.

The flap 12 at the opposite end of the blank is provided with a die-cut opening 18 through which the tabs 13 and 15 may be projected to 25 form an interlocking fastening between the flaps 11 and 12. The opening 18 is defined upon two sides by a pair of parallel edges 19 and 20 of equal length and of substantially the same length as the base lines of the tabs 13 and 15 indicated 30 by the dotted lines 16 and 17, respectively. The ends of the opening 18 are in the form of re-entrant angles 21 terminating in points positioned midway between the parallel sides 19 and 20.

The manner in which the fastening means described are interconnected is illustrated in Fig. 2, which is a view showing the flaps 11 and 12 as viewed from the back or inside of the cuff when the blank has been curved and just before these flaps are brought together in overlapping relation. In this view the tabs 13 and 15 are shown as having been bent inwardly from the plane of the blank so that their protruding curved ends may be easily inserted through the slot 18 with the tab 13 adjacent the side 20 thereof and the tab 15 adjacent the side 19 thereof. The tabs 13 and 15 are bent to and temporarily retained in the position illustrated in Fig. 2 by pressure of the thumb and forefinger of an operator engaged in 45 assembling the cuffs. As the flaps 11 and 12 are brought together in an abutting relationship with the tabs projecting through the opening 18, the tabs are released and returned by their inherent resiliency toward the plane of the blank. 50 55

Due to the angularity of the edges of the opening 18 formed by the re-entrant angles 21, release of the tabs 13 and 15 causes them to seek a position in the opening 18 with their bases, as indicated by the dotted lines 16 and 17 in Fig. 3, disposed contiguous to and coextensive with the sides 19 and 20 of the opening. As the bases of the tabs are substantially the same length as the sides of the opening, and as the tabs themselves project through the opening to lie flat against the inner side of the flap 12, the flaps 11 and 12 are securely held together by the fastening means, which tends to prevent relative movement in any direction of the overlapping flaps.

Fig. 4 illustrates the position assumed by the tabs 13 and 15 as viewed from the interior of the cuff after the fastening is complete, and Fig. 1 shows the appearance of the fastening means as viewed from the exterior of the cuff. The tabs 13 and 15 will normally lie flat against the interior of the flap 12, as shown in Fig. 4, but when the cuff is dropped over the top of a bottle, the pressure of the flaps against the side of the bottle further insures against their becoming disarranged or slipping out of the opening 18. It is desirable that the opening 18 be, as illustrated, of less length centrally than it is along its sides 19 and 20, but it is not essential that the shape thereof be exactly as shown, nor is it essential that the tabs 13 and 15 be semi-circular. While it is apparent that a secure fastening means would be provided should the opening 18 be eliminated, having instead thereof a pair of narrow slits formed along the lines 19 and 20

through which the tabs might be projected, the form of the invention here shown is preferred because of the greater ease of assembly. With the opening 18 shaped as shown, it is only necessary, in assembling the fastening means, that the end of the tab 13 be projected through one-half of the opening, and the end of the tab 15 through the opposite half thereof, and as the flaps 11 and 12 are brought toward their abutting positions, the bases of the tabs 13 and 15 will readily find their proper positions along the sides 19 and 20 of the opening.

While a specific embodiment of the present invention has been described in detail, it is of course to be understood that variations may be made in its construction within the scope of the appended claim.

Having thus described my invention, what I claim and desire to secure by Letters Patent is:

Fastening means for a paper cuff or the like comprising a pair of oppositely projecting substantially semi-circular tabs cut from one end of the cuff to bend out of the plane thereof, the opposite end of the cuff having an opening formed therein with two straight edges equal in length and spacing to the lines of bending of said tabs and two edges formed on re-entrant angles, whereby upon insertion of the curved ends of said tabs on opposite sides of said angles, the tabs will be guided to positions below the opening and projecting beyond said straight edges.

CLAUDE D. PAINTER.
